UNITED STATES PATENT OFFICE.

BENJAMIN A. WATTS, OF ST. LOUIS, MISSOURI.

SIPHON APPARATUS.

1,012,040.

Specification of Letters Patent. Patented Dec. 19, 1911.

Application filed September 15, 1910. Serial No. 582,188.

To all whom it may concern:

Be it known that I, BENJAMIN A. WATTS, a citizen of the United States, residing at St. Louis, State of Missouri, have invented 5 certain new and useful Improvements in Siphon Apparatus, of which the following is a specification.

My invention relates broadly to siphon apparatus and has particular reference to 10 apparatus of this character specially adapted for emptying receptacles such as wash-tubs.

An important object of the invention is to provide in a siphon apparatus of the above 15 mentioned character, an intake head having means to prevent the entrance of air into the head as the water level falls, to enable the liquid in the vessel to be withdrawn therefrom by siphonic action until a very 20 low level is reached, and to prevent any sediment or other solid matter contained in the water entering the intake head, thereby precluding the same entering into the siphon tube.

25 Other objects and advantages of this invention will be apparent in the course of the following description.

In the accompanying drawings forming a 30 part of this specification, and in which like numerals are employed to designate like parts throughout the same, Figure 1 is a perspective view of the siphon apparatus, shown in connection with a wash-tub, Fig. 2 is a central longitudinal vertical sectional view through the intake-head of the siphon apparatus, and Fig. 3 is a vertical cross-sectional view taken on line 3-3 of Fig. 2.

In the drawings wherein is illustrated a 35 preferred embodiment of my invention, the numeral 1 designates a table upon which is arranged a wash-tub 2, as shown. The tub 2 is partly filled with water, as indicated by the numeral 3. I provide a siphon apparatus 4 for drawing the water out of the tub. 40 This siphon apparatus comprises an intake-head 5, the shell 6 of which may preferably have the shape as shown. The lower side of this shell is formed open, as shown, and the lower edge of the shell is provided with 45 spaced teeth 7 which result from the formation of the recesses 8 upon said edge. One end of the shell 6 is tapered to form a nipple 9, screw threaded internally, as shown at 10, for detachable engagement with a 50 hose or conduit 11. The hose 11 is provided with a suitable externally screw threaded

member, (not shown) to fit within the nipple 9. The shell 6 is provided internally thereof with a section of material or web 12, which is preferably cast integral with the shell, as shown, and inclined longitudinally with relation to said shell. This web serves to divide the shell 6 into two compartments 13 and 14. Attention is called to the fact that the upper end of this web 12 terminates in a horizontal plane 60 slightly above the inner end of the nipple 9. By disposing the web 12 within the shell 6 in the manner shown, a tortuous channel for the intake of the water is thus formed and 65 serves to preclude the entrance of air into the shell 6 as the water level in the vessel 2 falls. This function of the web is probably due to the fact that by throttling the flow through the head 6, the suction effect tends 70 to draw in air as well as water when the level in the tub is low is much reduced; while the open end of the shell provides a 75 free and unobstructed intake for the water. I have found by actual experiment that with 80 an intake head constructed as shown and hereinafter claimed, the liquid in the vessel 2 can be drawn therefrom by siphonic action until a lower level is reached than is possible 85 with a like intake head with the web missing. The web also serves as a deflector for any sediment or other solid matter that may be present in the water, thereby tending to 90 preclude the entrance of the same into the siphon tube.

The numeral 14' designates a spigot, adapted for detachable connection with the outer end of the hose 11, for a purpose to be set forth.

In the use of the siphon apparatus, the 95 suction nozzle 5 is disposed within the tub 3, so that its teeth 7 engage the bottom of the tub, as illustrated in Fig. 1. The hose 11 or conduit which is connected with the suction nozzle, now has its outer end connected with the spigot 14', and said spigot actuated to supply water to the hose 11. The water fills the hose 11 and drives out the air which previously filled the same. The flow of water from the spigot is cut 100 off when the air bubbles stop rising from the suction nozzle 5. The outer end of the hose 11 is then lowered below the level of the water 3, whereby the water will be withdrawn from the tub 2, in accordance with 105 the operation of a siphon. If desired, the hose 11 may be made of a sufficient length 110

so that its outer end may reach to a sewer or the like, for discharging thereinto. In lieu of priming the siphon through the agency of the spigot 14', the hose may be filled 5 with water in any suitable manner, as by placing the entire siphon apparatus below the water 3 in the tub, until said apparatus is filled with the water.

I wish it understood that the form of my 10 invention herewith shown and described is to be taken as a preferred example of the same, and that certain changes in the size, shape and arrangement of parts may be resorted to without departing from the spirit 15 of my invention or the scope of the subjoined claims.

Having thus fully described my invention, I claim:

1. In siphon apparatus, an intake head 16 comprising a shell having its lower end formed open and provided with means near such lower end to permit of the entrance

of a fluid within the shell, said shell tapering toward one end thereof, a nipple connected with the reduced end of the shell, 25 and a web disposed within the shell and extending from the lower side of the nipple to a point near and spaced from the upper end of said shell.

2. In siphon apparatus, an intake head 30 comprising a shell having its upper end formed closed and its lower end formed open, said lower end being provided with a plurality of relatively short spaced teeth, a web disposed within said shell, extending longitudinally thereof and being inclined, and a conduit connected with said shell near the lower end of the inclined web.

In testimony whereof I affix my signature in presence of two witnesses:

BENJAMIN A. WATTS.
